METHOD OF AND APPARATUS FOR REELING
FILAMENTARY ARTICLESCharles B. Clotworthy, Jr., Brooklandville, Md.,
assignor to Western Electric Company, Incorporated,
New York, N. Y., a corporation of New
York

Application July 24, 1950, Serial No. 175,569

5 Claims. (Cl. 242—54)

1

This invention relates to methods of and apparatus for reeling filamentary articles and more particularly to methods of and apparatus for reeling flexible wires having a plurality of parallel conductors enclosed in a jacket.

Some types of multi-conductor wires used with communications apparatus have the individual conductors thereof positioned parallel to each other and enclosed in a jacket. When a wire having parallel conductors is wound around a takeup reel, at least one of the conductors travels around a shorter circumferential path than that of the other conductors. This difference in the length of the circumferential paths of the conductors causes the conductor or conductors formed around the shorter path to buckle and distort the jacket of the wire. The relative positions of the conductors must be varied as the wire is wound on the reel to prevent them from buckling and distorting the jacket.

An object of the invention is to provide new and improved methods of and apparatus for reeling filamentary articles.

Another object of the invention is to provide new and improved methods of and apparatus for reeling flexible, multi-conductor cordage.

A method of distributing and reeling a filamentary article illustrating certain features of the invention, comprises winding such an article in a series of convolutions, and turning the article about its longitudinal axis as it is wound throughout each convolution to prevent the article from buckling as it is formed into said convolutions.

An apparatus illustrating certain features of the invention comprises means for winding a filamentary article in a series of convolutions, and means for turning the article about its longitudinal axis throughout the convolutions on the winding means thereby preventing the article from buckling as it is wound thereon.

A clear understanding of the invention will be had from the following detailed description of a method and an apparatus forming specific embodiments thereof, when read in conjunction with the appended drawings, in which:

Fig. 1 is a plan view of a strand distributing and reeling apparatus embodying certain features of the invention;

Fig. 2 is an enlarged, horizontal section taken along line 2—2 of Fig. 1;

Fig. 3 is an enlarged transverse section taken along line 3—3 of Fig. 1, and

Fig. 4 is an enlarged transverse section taken along line 4—4 of Fig. 1.

Referring now to the drawing, and more par-

2

ticularly to Fig. 1, a reel 10 for coiling a flexible, multi-conductor wire 11 is mounted rotatably between a support 14 and a housing 15 provided on a base 16. The reel 10 is driven by a motor 18 through conventional suitable gearing (not shown) provided in the housing 15.

The wire 11 includes a plurality of individually insulated conductors 20, 21 and 22 (Fig. 3) enclosed in a flexible jacket 23. The jacket 23, as shown, is a solid mass of insulating material which has been extruded over the conductors 20, 21 and 22. The jacket may be made of one of various elastomeric compounds that may be extruded over the conductors and cured into a tough, elastic jacket by the application of heat and pressure, or may consist of one of various types of thermoplastic compounds which may be used for insulating and jacketing conductors. If desired, the jacket may consist of a knitted or braided textile material, such as cotton, which may be impregnated, if necessary. The conductors 20, 21 and 22 are positioned in the jacket 23 with their axes parallel to the longitudinal axis of the complete wire throughout its entire length, and the jacket 23 holds the conductors 20, 21 and 22 in that position.

For purposes of illustrating the present invention it will be assumed that the jacket 23 is made of a thermoplastic material, such as polyvinyl chloride, and that the wire 11 is advanced continuously toward the reel 10 at a substantially constant linear speed from apparatus (not shown) designed to extrude the jacket around the conductors.

The wire 11 (Figs. 1 and 2) passes under a sheave 24 mounted rotatably on an arm 25 secured to a post 26 journaled in a bearing 28 fixed on the end of a bracket 30. A compression spring 31 positioned over the post 26 between the arm 25 and the bracket 30 holds a pin 33 in either of slots 34—34 provided in the end of the bearing 28. A handle 35 is provided on the end of the post 26 for sliding the post in the bearing so as to disengage the pin from the slot in which it is engaged and for turning the post until the pin 33 is positioned in the desired slot. This arrangement of the pin 33 and the slots 34—34 in the bearing 28 provides a means for varying the position of the sheave 24 with respect to the bracket 30.

The bracket 30 is secured rigidly to a nut 37 threadedly engaging a traversing screw journaled in the supports 14 and 15 and driven by the motor 18 through suitable conventional automatically reversing gearing (not shown) pro-

vided in the housing 15. The nut 37 is provided with an ear 40 which slidably engages a guide rod 41 secured to the support 14 and the housing 15 parallel to the traversing screw 38 and horizontally aligned with the traversing screw. 5 The nut is provided with a second ear 42 which slidably engages a rod 43 secured in the support 14 and housing 15 parallel to the traversing screw 38 and vertically aligned with the traversing screw (Fig. 2). The wire 11 travels to the left, as viewed in Fig. 1, and around the under side of the sheave 24, upwardly around a portion of a roller 45, preferably of metal, mounted rotatably on a post 46 secured to the bracket 30, between guide rollers 48-48 mounted rotatably on the nut 37 and then to the reel 10. When the motor is driving the reel 10 and the traversing screw 38, the reel 10 takes up the wire 11 and the nut 37 is reciprocated across the winding surface of the reel so that the rollers 48-48 carried thereby distribute the wire 11 uniformly on the winding surface of the reel.

The post 46 is mounted on the bracket 30 so that the axis of rotation of the roller 45 is disposed at a predetermined angle with respect to the sheave 24 and the longitudinal axis of the wire. The rollers 48-48 and the sheave 24 hold the wire in a path of travel perpendicular to the axis of the reel, and as a result, the wire travels diagonally across the periphery of the roller 45, as shown in Fig. 1. The wire rotates the roller 45 about its axis, and since its axis of rotation is inclined with respect to the longitudinal axis of the wire 11, such rotation of the roller rotates the portion of the wire 11 between the reel 10 and the sheave 24 in a counterclockwise direction, as viewed in Fig. 3, about its longitudinal axis, and the conductors assume the positions shown in Fig. 4. Until slippage occurs between the wire and the roller 45, each increment of wire first engages the portion of the roller 45 near the upper end thereof, as viewed in Fig. 1, and, as each increment is pulled on over the roller, tension on the wire pulls that increment away from the upper end of the roller toward the lower end of the wire, thereby rolling the 45 wire along the roller. The wire is rotated about its longitudinal axis until the frictional contact between the wire and the surface of the roller is overcome by the torsional stresses built up in the jacket 23 and in the individual conductors 20, 21 and 22, at which point the wire slips on the roller 45 and unwinds in the opposite direction and releases these torsional stresses. This winding and unwinding occurs at successive intervals and produces an oscillation of the wire about its longitudinal axis, which first twists the individual conductors 20, 21 and 22 in a counterclockwise direction about the longitudinal axis of the wire from their normal parallel relationship to a helical relationship, and then the conductors unwind in the opposite direction about the longitudinal axis of the wire until they approach their normal parallel relationship.

The wire is taken up by the reel 10 as it oscillates in this manner, whereby the portions of the conductors in adjacent convolutions on the reel are twisted out of their original parallel relationship and their respective circumferential paths of travel around the winding surface of the reel are substantially equal. This equalizing of 70 the circumferential paths of travel of the conductors in the convolutions wound on the reel prevents any conductor in each convolution from having a circumferential path of travel shorter than that of the other conductors in the same 75

convolution, which condition would cause the conductor having the shorter circumferential path to buckle and distort the jacket 23 of the wire.

Operation

Let it be assumed that the wire 11, which is advancing to the left at a constant linear speed, when viewed in Fig. 1, has its individual, parallel conductors 20, 21 and 22 positioned as shown in Fig. 3, at a point just to the right of the sheave 24. At this point, two of the conductors 21 and 22 are positioned below the longitudinal axis of the wire 11 and the third conductor 20 is positioned above the longitudinal axis of the wire. The wire passes under the sheave 24, over the upper portion of the roller 45 and between the guide rollers 48-48 to the takeup reel 10. When the motor 18 is energized, it rotates the reel 10 to take up the wire in a series of helical convolutions around its winding surface, and rotates the traversing screw 38 to reciprocate the nut 37, the rollers 48-48 and the bracket carrying the roller 45 and the sheave 24 transversely across the winding surface of the reel. As the reel takes up the wire 11, the guide rollers 48-48 distribute the wire 11 uniformly on the winding surface of the reel.

If the wire 11 were wound directly around the winding surface of the reel 10 with the conductors 20, 21 and 22 parallel to each other, the conductors 21 and 22 positioned below the longitudinal axis would be formed around a shorter radius than that of the conductor 20, which is positioned above the longitudinal axis. As a result, a difference in the length of the circumferential paths of travel of the upper and lower conductors would occur and cause the lower conductors to buckle and distort the jacket 23 of the wire.

This tendency of the conductor positioned below the longitudinal axis of the wire to buckle is prevented by the roller 45 because, as the wire 11 travels around the upper portion of the roller 45, it rotates the roller and the roller in turn rotates the portion of the wire between the sheave and the reel and twists the conductors in a counterclockwise direction about the longitudinal axis of the wire, and the conductors assume the positions shown in Fig. 4. The roller 45 rotates the wire until the torsional stresses built up in the jacket 23 and the individual conductors overcome the frictional contact between the wire and the surface of the roller, whereupon the stresses cause the wire to slip on the roller and unwind the conductors about the longitudinal axis of the wire in the opposite direction. As soon as these torsional stresses are relieved, the roller 45 starts to twist the wire in its original direction. The resulting oscillation of the conductors and the wire continuously varies the relative position of the individual conductors with respect to the longitudinal axis of the wire.

The major portion of the oscillation of the wire 11 occurs between the point of contact between the wire and the winding surface of the reel and the point of contact between the wire and the sheave 24. The sheave 24 is spaced a predetermined distance from the reel 10 so that a predetermined number of rotations of the wire about its longitudinal axis occurs in the portion of the wire therebetween before the jacket and conductors build up sufficient torsional stresses therein to cause the wire to slip on the roller and then unwind and rotate the wire in an opposite direction. This oscillation of the wire

about its longitudinal axis between the sheave 24 and the reel 10 continually varies the relative positions of the conductors with respect to the longitudinal axis of the wire at irregular intervals, and maintains the circumferential length of the conductors in the convolutions wound around the reel substantially equal, thereby preventing the conductors from buckling and distorting the jacket of the wire.

The amount of twist imparted to the wire by the roller 45 is determined by the angle at which the roller is positioned with respect to the longitudinal axis of the wire, the size of the roller 45, the diameter of the wire, the material from which the jacket 23 is made, the distance between the reel 10 and the sheave 24.

In the structure described hereinabove, the roller 45 is eight inches in diameter and is inclined at an angle of about 55° or 60° with respect to the longitudinal axis of the wire, and the reel 10 and sheave 24 are spaced 33 inches between centers. The wire 11 has three conductors enclosed in a polyvinyl chloride jacket 23 and has a diameter of .170 inch. With the sheave 24 positioned so that the wire 11 makes approximately one-quarter turn around the roller 45, it was found that the roller 45 rotates the portion of the wire between the reel and the sheave 24 about one turn in a counterclockwise direction about its longitudinal axis, and the conductors assume their positions shown in Fig. 4. After the wire rotates about one turn, it slips on the surface of the roller and unwinds in an opposite direction and the conductors assume their respective positions, as viewed in Fig. 3. The position of the sheave 24 with respect to the roller may be adjusted to increase or decrease the amount of contact between the wire and the roller and thereby increase or decrease the amount of rotation imparted to the wire by the roller 45.

It is to be understood that when the conductors 20, 21 and 22 are enclosed in a textile jacket, it may be desirable to provide a rubber surface on the roller 45 to obtain sufficient frictional contact between the wire and the roller to obtain the desired rotation of the wire by the roller.

The above-described method and apparatus for coiling a multi-conductor wire on a reel may be modified to suit various types of filamentary articles without departing from the spirit and scope of the invention. The term "filamentary article," as used herein and in the annexed claims, is generic to various articles of indefinite length and is meant to embrace, wire rope having parallel elements, insulated wires having a plurality of conductors enclosed in a jacket so that they are parallel, various types of textile articles, and all articles having parallel elements which would buckle when wound around a takeup reel, or the like.

What is claimed is:

1. An apparatus for reeling filamentary articles having a plurality of elements parallel to the longitudinal axis of the article, which comprises a reel for coiling such an article in a series of convolutions around the winding surface thereof, means for distributing the convolutions uniformly across the winding surface of the reel, and a roller secured on said distributing means so as to be engaged by the article being reeled, said roller being mounted in such a position with respect to the longitudinal axis of the article that it rotates the article about its longitudinal axis a predetermined number of turns at successive intervals as it is wound on the reel, said rotation of the article varying the relative positions of

the elements throughout each convolution wound on the reel, thereby preventing the elements from buckling as the article is wound on the reel.

2. An apparatus for distributing and reeling wire having a plurality of individually insulated conductors arranged parallel to each other and enclosed in a flexible jacket, which comprises a reel for taking up such a wire in a series of convolutions around its winding surface, means for guiding the wire to the reel, means driven in timed relationship with respect to the reel for reciprocating the guiding means so as to distribute the convolutions uniformly across the winding surface of the reel, and a roller mounted on the distributing means at an acute angle with respect to the longitudinal axis of the wire for rotating the wire about its longitudinal axis as it is wound on the reel, said rotation of the wire varying the relative positions of the conductors so that they are not parallel to the longitudinal axis of the wire throughout the convolutions on the reel, thereby preventing the conductors from buckling and distorting the jacket of the wire.

3. An apparatus for distributing and reeling a wire having a plurality of individual conductors arranged parallel to each other and enclosed in a flexible jacket, which comprises a takeup reel, means for rotating the reel to wind such a wire in a series of helical convolutions on the reel, means for guiding the wire to the reel, a traversing screw threadedly engaging the guiding means driven by the motor in timed relation with respect to the reel for reciprocating the guiding means to distribute the convolutions uniformly across the winding surface of the reel, a sheave rotatably mounted on the guiding means under which the wire passes as it travels to the reel, and a roller reciprocated with the guiding means and positioned at an angle with respect to the longitudinal axis of the wire for rotating the wire about its longitudinal axis a predetermined number of turns at successive intervals, said rotation of the wire about its longitudinal axis varying the relative positions of the conductors with respect to the longitudinal axis of the wire throughout each convolution wound on the reel to prevent the conductors from buckling as the wire is wound on the reel.

4. An apparatus for distributing and reeling wire having a plurality of individually insulated conductors arranged parallel to each other and enclosed in a flexible jacket, which comprises a reel, a motor for driving the reel to take up such a wire in a series of convolutions around the winding surface of the reel, means driven by the motor for distributing the convolutions uniformly across the winding surface of the reel, a sheave rotatably mounted on the distributing means in such a position that the wire passes under the sheave as it travels to the reel, and a roller rotatably mounted on the distributing means and inclined at an angle toward the sheave for rotating the portion of the wire between the sheave and the reel about the longitudinal axis of the wire a predetermined number of turns at successive intervals until the torsional stresses of the wire overcome the frictional contact between the wire and the roller and the wire unwinds in an opposite direction to the rotation imparted thereto by the roller, said oscillation of the wire at successive intervals as a result of its rotation by the roller varies the relative positions of the individual conductors so that they are not parallel to the longitudinal axis of the wire throughout and thereby prevents as the convolutions are

wound on the reel the conductors from buckling and deforming the jacket of the wire as it is wound on the reel.

5. The method of reeling a wire having a plurality of conductors enclosed in a jacket so that they are parallel to the longitudinal axis of the wire, which comprises continuously advancing such a wire to a takeup reel, winding the wire on the reel, and continuously exerting a predetermined rolling force on the wire at a predetermined point in the path of the wire, said force and said distance being such that the wire repeatedly is twisted and untwists itself, whereby

5
10

the wire wound on the reel has alternate twists in opposite directions.
